UNITED STATES PATENT OFFICE.

FRANK D. GOULD, OF OAKLAND, CALIFORNIA.

AUTO TOP.

Application filed September 18, 1923. Serial No. 663,381.

This invention relates to an auto top and especially to a sliding window for effecting a closure of the sides of the top as is exemplified in my copending application entitled 5 "Auto top," filed October 12th, 1921, Serial No. 507,234.

The object of the present invention is to generally improve and simplify the construction and operation of sliding windows of the 10 character described. I accomplish this object first, by providing a pair of resilient spring arms by which the window is suspended from an overhead rail and whereby a limited vertical movement of the window 15 with relation to the rail and the body of the car is permitted; secondly, by providing a pair of shoes which permit sliding of the window and which also serve as gripping members to secure and lock the window at 20 any point intermediate the ends of the rail; and third, by providing means for actuating the gripping members as will hereinafter be described.

One form which my invention may assume 25 is exemplified in the following description and illustrated in the accompanying drawings, in which:-

Fig. 1 is a side elevation of an automobile top showing the windows in extended position.

Fig. 2 is an enlarged cross section taken on line 2—2 of Fig. 1.

Fig. 3 is an enlarged side elevation of one of the windows.

Fig. 4 is a cross section on line 4—4 of Fig. 3.

Fig. 5 is a perspective view of one of the shoes and the connected spring arm.

Referring to the drawings in detail, A indicates the body of an automobile, 2 the usual form of hinged doors, 3 the hood or forward portion of the car, 4 the windshield, and B the top proper.

The top here shown consists of a permanent rigid frame secured to the body and to the windshield. The shape of the top and the detail construction of the same is of no particular importance, as it forms no part of the present invention, and as it may furthermore be changed to suit varying conditions.

Formed as a portion of the top is a permanent back section 6 and a pair of stationary or permanent side sections 7 in which are mounted stationary windows 8, one side section and window being disposed on each side

of the car. Also disposed on each side of the top is a pair of sliding windows 9 and 10. These windows are arranged in pairs, one pair on each side, and these windows are 60 adapted to be moved rearwardly into alignment with the stationary windows 8, or to be extended forwardly of the stationary windows to partially or wholly enclose the car.

The mechanism employed for the purpose 65 of supporting the windows and for locking the same whether in extended or retracted position forms the subject matter of the present invention.

The windows are supported from overhead 70 tracks or rails such as indicated at 11 and 12, there being one pair of rails arranged in each side of the top. The top proper is channeled on each side as at 13 to receive the rails (see Fig. 2), and the rails are secured within 75 these channeled portions in any suitable manner or as here illustrated, by being secured to longitudinal extended spacing strips 11^a and 12^a. The track 11 supports the window 9 and the track 12 the window 10. The 80 mechanism employed for the purpose of supporting the windows is identical in each instance and the description of one will therefore suffice.

To clearly illustrate the mechanism, reference may be made to Fig. 3, in which 11 indicates one of the overhead rails from which the window 9 is suspended in such a manner that it may be moved from end to end of the rail to extended position or retracted position 90 as desired. One of the purposes of the present invention is to permit locking of the window at any point intermediate the extended or retracted position. I will accomplish this as follows:

Slidably mounted on the rail 11 are a pair of shoes such as indicated at 14 and 15. Secured to the shoes are a pair of flat spring arms such as indicated at 16 and 17. The outer ends of the arms are secured to their 100 respective shoes in any suitable manner and may, in fact, be formed integral therewith if desired. The opposite or inner ends of the spring arms are secured to the upper rail of the window frame by means of screws or 105 the like such as indicated at 19. The spring arms form a resilient support for the window and as such permits a limited vertical movement of the same. This vertical movement is of considerable importance as it first of all 110 permits the window to be lowered and forced into contact with a bottom guideway such as

indicated at 20, and consequently permits tilting of the shoes 14 and 15 so that they will grip the rail 11 and thereby secure the window against further movement. The vertical movement is imparted to the window through means of a lug 21. This lug is pivotally mounted in the upper rail of the window frame as indicated at 22, and the upper end of the lug engages the under side of the rail 11. Means are employed for imparting a rocking movement to the lug 21 so that it may be swung from the full line position shown at 21 to the dotted line position indicated at 21^a, or to the second dotted line position indicated at 21^b.

The means employed and here illustrated consist of a pair of links 23 and 24 which are pivotally secured at one end to the lug 21 and at their opposite ends two bell cranks 25 and 26. These bell cranks are pivotally mounted at opposite ends of the top rail 18 of the window frame, and they are in turn connected by means of links 27 and 28 to crank arms 29 and 30 secured on the shafts 32 and 31. The outer ends of the shafts 31 and 32 project through the forward face of the window frame as shown in Fig. 4, and they are each provided with a turning knob as indicated at 33. If the knob on the left hand side is turned in the direction of the arrow —a—, crank arm 29 swings upwardly and so does the link 27. Bell crank 26 will thus swing in the direction of arrow —b—, and lug 21 will move from the position indicated at 21^b to the dotted line position indicated at 21^a. It will here engage the under side of the rail 11 and thus force the window frame in a downward direction, this downward movement being permitted due to the resilient connection or spring like arms 16 and 17 which form a connection between the window frame and the respective shoes. When the window is thus forced downwardly, it engages the bottom guide 20, and is thus forced against the same with such a pressure that a sliding movement of the window is prevented.

It will also be noted that as the spring arms 16 and 17 are bent downwardly, the shoes 14 and 15 will assume a slightly tilted position with relation to the rail 11. This is important as it will cause the shoes to grip the rail and thus positively lock the window against sliding movement.

As the lug 21 will engage the lower side of the rail at any point intermediate the ends of the rail, it is obvious that the window can be locked in any position desired, whether fully retracted or extended or at any intermediate point.

It will be seen that a three point lock is obtained, as a resilient rubber shoe 35 is secured to the bottom of the window frame. This shoe is slightly compressed when the window is forced downwardly against the bottom guide, and such forms a frictional

contact between the window and the guide which prevents movement of the window at the lower end, the other locking points being obtained by the tilting of the shoes which grip the rail at the upper ends of the window frame.

The invention is particularly suited for sliding windows, such as employed in auto tops, as it eliminates the necessity of accurate workmanship, and it furthermore takes care of any spring or twist in the top or the body. That is, the movement of the lug 21 is such that the vertical movement imparted to the window may be one-quarter of an inch or more. If the spacing between the rails and the bottom guide happens to vary to a slight extent, it would make no material difference as far as the locking arrangement is concerned, as the lock or lug 21 would be equally effective whether the movement happened to be one-quarter or one-sixteenth of an inch.

It can furthermore be seen that it would make no difference if one end of a rail should happen to be a little high and the opposite end a little low, as this would be taken care of by one spring arm yielding to a greater extent than the other.

Rattle and vibration as far as the window is concerned is taken care of under all conditions, as a positive lock is secured whether the window is fully extended, retracted or otherwise.

The cost of installation is materially decreased, as accuracy in workmanship may be more or less eliminated, and as the mechanism employed is exceedingly simple and easy to install.

By referring to Figs. 3 and 4, it will be noted that the front face of a window frame is grooved or channeled as indicated at 45 to receive the various links, bell cranks, etc., whereby the lock is operated. A front plate 46 covers the channel, and the links, bell cranks, etc. are thus hidden from view. The only parts of the mechanism which appear are the turning knobs 33, as they are secured on the outer ends of the shafts which project through the plate 46.

By referring to Fig. 2, it will be noted that the upper ends of the shoes are hook shape as indicated at 47. This is important as the hooks grip the upper portion of the rail, while the flat portions indicated at 48 grip the lower side of the rail when the shafts are tilted.

Having thus described my invention, what I claim and desire to secure by Letters Patent is:—

1. The combination with a horizontally sliding closure for vehicles, of an overhead track, hangers having hooks to fit slidably over the track, and connecting means between the hangers and the closure, whereby when the closure is depressed the hooks are caused to tilt and grip the track.

2. The combination with a horizontally sliding closure for vehicles, of an overhead track, hangers slidably mounted on the track, resilient connecting means between the hangers and closure, whereby the latter is normally held in slightly raised position, to permit free sliding movement, and means to depress the closure, whereby to cause the hangers to tilt and grip the tracks.
- 10 3. In a device of the character described, an overhead rail, a window, a pair of shoes slidably mounted on the rail and from which the window is suspended, and means for imparting a tilting movement to the shoes at any point intermediate the ends of the rail to cause the shoes to grip the rail and lock the window against sliding movement.
- 15 4. In a vehicle top of the character described, an overhead track, a lower guideway, a horizontally movable sash disposed between the track and guideway, slidable hangers arranged on the track, resilient means connecting the hangers with the sash in a manner to maintain the sash slightly raised, and means for depressing the sash so as to bring it into more intimate contact with the lower guideway, said resilient means acting when the sash is depressed to effect a tilting and gripping engagement between the hangers and
- 20 the track.
- 25 5. In a vehicle top of the character described, an overhead track, a lower guideway, a sliding sash disposed between the track and guideway, hangers slidably mounted on the track, resilient means connecting the sash to said hangers in a manner to maintain the sash in slightly raised position, so as to per-
- mit free sliding movement thereof, and movable means arranged between the sash and the track for depressing the sash, to tilt the hangers and cause them to grip the tracks.
- 30 6. In an auto top of the character described, an overhead rail, a pair of shoes slidably mounted thereon, a pair of spring arms fastened one to each shoe, a window disposed below the rail and fastened to the opposite ends of said spring arms, said spring arms forming a resilient support between the shoes and the window and permitting a limited vertical movement of the window with relation to the rail, and means for exerting a downward pressure on the spring arms to cause the same to tilt the shoes which will thereby grip the rail and lock the window against sliding movement on the rail.
- 35 7. In an auto top of the character described, an overhead rail, a pair of shoes slidably mounted thereon, a pair of spring arms fastened one to each shoe, a window disposed below the rail and fastened to the opposite ends of said spring arms, said spring arms forming a resilient support between the shoes and the window and permitting a limited vertical movement of the window with relation to the rail, a lug pivotally mounted on the window and engageable with the lower side of the rail, and means for imparting a turning movement thereto to force the window downwardly so as to bend the spring arms and thereby tilt the shoes with relation to the rail, said tilting movement of the shoes causing the shoes to grip the rail and to lock the window against sliding movement.
